LIGHTING FIXTURE

Filed June 3, 1929

Inventor:
Albert J. D. Ohm
By W. O. Bell atty.

UNITED STATES PATENT OFFICE.

ALBERT J. D. OHM, OF OAK PARK, ILLINOIS, ASSIGNOR TO R. WILLIAMSON & COMPANY, OF CHICAGO, ILLINOIS, A CORPORATION OF ILLINOIS.

DESIGN FOR A LIGHTING FIXTURE.

Application filed June 3, 1929. Serial No. 31,511. Term of patent 7 years.

To all whom it may concern:

Be it known that I, ALBERT J. D. OHM, a citizen of the United States, residing at Oak Park, in the county of Cook and State of Illinois, have invented a new, original, and ornamental Design for Lighting Fixtures, of which the following is a specification, reference being had to the accompanying drawing, forming a part thereof, in which the figure is a perspective view of my new design.

I claim:

The ornamental design for a lighting fixture, as shown.

ALBERT J. D. OHM.
